CLAIM

The ornamental design for a flexible circuit board with connectors, as shown and described.

DESCRIPTION

FIG. 1 is a perspective view of a flexible circuit board with connectors, according to an embodiment of the invention; FIG. 2 is an enlarged view of the connectors of the flexible circuit board of FIG. 1;

FIG. 3 is a top view of the flexible circuit board with connectors of FIG. 1;

FIG. 4 is a bottom view of the flexible circuit board with connectors of FIG. 1;

FIG. 5 is a first side view of the flexible circuit board with connectors of FIG. 1;

FIG. 6 is a second side view of the flexible circuit board with connectors of FIG. 1;

FIG. 7 is a third side view of the flexible circuit board with connectors of FIG. 1;

FIG. 8 is a fourth side view of the flexible circuit board with connectors of FIG. 1;

FIG. 9 is another perspective view of the flexible circuit board with connectors of FIG. 1, installed in a casing of a lighting device; and,

FIG. 10 is an enlarged view of the connectors of the flexible circuit board of FIG. 9.

Broken lines present on the interior surface of the flexible circuit board with connectors in FIGS. 1-8 show portions of the circuit board that form no part of the claimed design. Broken lines in FIGS. 9 & 10 show environmental subject matter that likewise forms no part of the claimed design.

1 Claim, 8 Drawing Sheets
